INK FEEDING DEVICE

Joseph Sinkovitz, Pittsburgh, Pa., assignor to
Miller Printing Machinery Co., Pittsburgh, Pa.,
a corporation of Pennsylvania

Application April 1, 1937, Serial No. 134,343

8 Claims. (Cl. 101—357)

My invention pertains to ink feeding devices, such as are employed for supplying ink to the inking means of a printing press, as, for instance, to the form rollers of a flat bed printing press. Such ink feeding devices commonly include a number of rollers, some of metal and some of gelatine or other composition, which rotate in contact with one another for the purpose of breaking up the somewhat uneven deposit of ink 5 as originally received from the fountain and producing a regular and even film of ink for transfer to the form rollers. When the printing press is stopped for any material period of time, those of the rollers which are made of composition are liable to become distorted by the creation of flat 10 portions at the places where the composition has remained pressed against the companion roller or rollers. To avoid this, it is common practice for the operator to remove the composition rollers when the press is stopped for any considerable 15 period. This involves material work and expenditure of time, which it is a main object of my present invention to avoid. I attain this object by providing a construction in which a plurality of the composition rollers are made movable into and out of contact with their companion rollers, and in which the manipulation of a single actuating member serves to move the several composition rollers away from their companion 20 rollers or back against such rollers, as conditions may require. Thus when the printing press is stopped, contact can be broken between the several rollers by a single operation, and as easily reestablished when the press is to be started again.

An ink feeding device constructed in accordance with my invention is shown, by way of example, in the accompanying drawings and described in the following specification. It is to be understood, however, that the invention can be embodied in other forms, and that changes can be made in the particular form described and shown, without exceeding the spirit thereof, as defined in the appended claims.

45 In the drawings:

Fig. 1 is a plan of the ink feeding device;

Fig. 2 is a side elevation of the same with one of the side frames removed, the view being substantially as seen from the line II—II of Fig. 1;

50 Fig. 3 is a section on the line III—III of Fig. 1;

Fig. 4 is a diagrammatic view of the members shown in Fig. 2, showing the means for driving certain of such members;

Fig. 5 is a side view of the means for operating 55 the ductor roller;

Fig. 6 is a front view, as seen from the right of Fig. 5, showing certain parts of the means for operating the ductor roller;

Fig. 7 is a side view of the actuating lever; and

Fig. 8 is a side view similar to Fig. 2, but showing the various rollers moved out of contact with their companion rolls.

Referring now to Figs. 1 and 2, the device includes a pair of side frames 10 and 11, between which the various rollers, etc., are placed and which serve as a support for the ink-fountain 12 with its fountain roll 13. A composition ductor roller 14 is made to oscillate between the fountain roll 13 and a steel vibrator roll 15, so as to transfer ink periodically from the fountain roll 13 to such vibrator roll. Between the side frames there is rotatably mounted an ink-drum 16 upon which the ink is spread uniformly preparatory to being transferred to the form rollers (indicated diagrammatically and designated *f*) of the press. 20 Composition rollers 17 and 18 engage the ink-drum. Of these, the roller 17 also engages the vibrator roll 15, so as to transfer ink therefrom to the ink-drum. A steel rider roll 19 engages between the composition rollers 17 and 18. A 25 third composition roller, 20, engages between the ink-drum and a steel vibrator roll 21 which latter rides between two of the form rollers and thus transfers ink to the latter.

The ink-drum and the vibrator rolls 15 and 21 30 are positively driven. To this end, a stud shaft 22 carries a gear 23 (which may be driven by a rack on the type-bed of the press). The gear 23 meshes with gears 24 and 25 associated with the ink-drum and the vibrator roll 21, respectively. 35 A shaft 26 is mounted between the side frames and carries a gear 27 rotatably mounted thereon. The gear 27 is engaged by the gear 24 of the ink-drum and engages a gear 28 associated with the vibrator roll 15.

As thus far described, the ink feeding device is of a character well known in the art, my present invention, as has been stated, being directed to the provision of an easy and quick means for breaking contact between the composition rollers 40 and their companion rolls. In the particular construction now being described, the rider-roll 19 is first raised from the composition rollers 17 and 18, then the roller 17 is raised from the ink-drum, and then the roller 18 is similarly raised. This 45 is effected by the operation of a single actuating member, which operation also effects the movement of the composition roller 20 away from the ink-drum and vibrator roll 21, as well as movement of the ductor roller 14 away from the foun- 50 55

tain roll 13, if the ductor roller happens to be in contact with the fountain roll at the time the actuating member is operated.

The actuating member consists of a lever 29 (Fig. 7) pivoted to the side frame 10 and formed with a slot 30 for receiving a pin projecting from a crank 31 secured to the shaft 26. The shape of the slot is such that when the lever is pulled rearward (that is, to the right from the normal position shown in full lines in Fig. 7) the shaft 26 will be rocked clockwise. Upon the shaft 26, adjacent the inside of the frame 10, is secured an actuating head 32. This may, of course, be duplicated at the opposite end of the shaft 26 if desired.

16 The rider roll 19 has its bearing in a pair of levers 33, one at each side of the device, which extend from hubs 34 rockably mounted on studs 35 extending inwardly from the side frames. One of these levers is provided with a tail piece 36, the end of which enters a notch 37 formed in the periphery of the actuating head 32. Thus it will be seen that clockwise movement of the head has the effect of raising the levers 33 and lifting the rider roll 19.

25 The composition roller 17 has its bearing in a pair of levers 38 extending from hubs 39 rockably mounted on the above-named studs 35. The adjacent ends of the hubs 39 and 34 are formed with inter-engaging bosses 41 and 42 respectively (Fig. 3), a slight clearance being left between the bosses of the respective hubs. When the levers 33 begin to rise, as above described, the levers 38 will not at first be affected, because of the clearance; but when the bosses 42 35 have come into contact with the bosses 41 (Fig. 8), the levers 38 will begin to follow the levers 33 upward, thereby lifting the composition roller 17 away from the ink-drum and the vibrator roll 15. The hubs 39 of the levers 38 are formed 40 with lugs 43 carrying adjustable stop screws 44 adapted to engage bosses 45 formed on the side frames. This ensures that the roller 17 shall stop in the desired relation with the ink-drum and the vibrator roll 15 when the roller 17 is 45 returned to its operative position.

The composition roller 18 is mounted in bearings which are vertically movable in the side frames. Its shaft, or collars 46 or the like thereon, is adapted to be engaged by feet 47 formed 50 at the ends of extensions 48 of the levers 33. Clearance is left between the feet 47 and the collars 46, with the result that the levers 33 and rider roll 19 will have risen through a material 55 distance before the roller 18 begins to be lifted from the ink-drum.

The composition roller 20 has its bearing in a pair of levers 49 pivoted to the side frames. One of these levers is provided with a tail piece 50, the end of which enters a notch 51 formed in 60 the actuating head 32. Clearance is provided between the walls of the notch 51, and the end of the tail piece; so that raising of the lever 49 does not begin until the actuating head 32 has completed part of its rocking movement. Thereafter the composition roller 20 is lifted away from the ink-drum and the vibrator roll 21. The levers 49 are formed with stop portions 52 adapted to engage bosses 53 extending inwardly from the side frames, for the purpose of limiting the 65 movement of the roller when it is returned to its operative position.

One of a number of available means for rocking the ductor roller 14 to and fro between the fountain roll 13 and the vibrator roll 15, is shown 70 in Figs. 5 and 6. In this construction, the ductor

roller has its bearing in an arm 54 which extends upwardly from a rock shaft 55. A second arm, 56, extends downwardly from the rock shaft and is adapted to be engaged by a push rod 57 connected, through a link 58, with a rotating crank 59. A spring 60 normally holds the arm 56 in engagement with the end of the push rod. From this construction it will be seen that the rotation of the crank 59 causes the ductor roller first to be moved against the vibrator roll 15 and then to be returned, under the action of the spring 60 against the fountain roll 13.

In providing for the movement of the ductor roller away from the fountain roll when the press is stopped, I secure to the shaft 55 a vertical arm 15 61 provided with a pin 62 which enters an elongated slot in a link 63. This link is connected to the actuating head 32 by means of a pin 64 which enters a hole 65 (Fig. 2) in the actuating 20 head.

Of course, the ductor roller can be in various positions when the press is stopped. If, however, the press is stopped at a time when the ductor roller is in engagement with the fountain roll, the rotation of the actuating head 32 will 25 cause the link 63 to pull the ductor roller away from the fountain roll.

It will be seen from the foregoing that, supposing the various rollers to be in the operative position shown in Fig. 2, all that is necessary to break the engagement between them and their companion rolls is for the pressman to shift the lever 29 from the position shown in full lines in Fig. 7 to the position shown in dotted lines. Similarly, all that is necessary in order to return the rollers to their operative locations is for the pressman to push the lever back to its original position.

Having thus fully described my said invention, what I claim as new and desire to secure by Letters Patent is:

1. In an ink feeding device, the combination with a rotary ink drum, an ink-supply roll, a roller contacting said roll and said drum for transferring ink from the former to the latter, a second roller engaging said drum, and a rider-roll engaging between said first and second rollers, of means for mounting said first roller for movement relatively to said ink-supply roll and said drum, means for mounting said second roller for movement relatively to said drum, means for mounting said rider-roll for movement relatively to said rollers, and a single means for first moving said rider-roll away from said rollers, then moving said first roller away from said ink-supply roll and said drum, and then moving said second roller away from said drum.

2. In an ink feeding device, the combination with a rotary ink drum, an ink-supply roll, a roller contacting said roll and said drum for transferring ink from the former to the latter, a second roller engaging said drum, and a rider-roll engaging between said first and second rollers, of means for mounting said first roller for movement relatively to said ink-supply roll and said drum, means for mounting said second roller for movement relatively to said drum, means for mounting said rider-roll for movement relatively to said rollers, an actuating member, and connection means between said member and said mounting means whereby actuation of said member effects first a movement of said rider-roll away from said rollers, then a movement of said first roller away from said ink-supply roll and 75

said drum, and then a movement of said second roller away from said drum.

3. In an ink feeding device for printing presses, the combination with an ink-supply roll, an ink drum, a roller contacting said ink-supply roll and said drum, a second roller contacting said drum and disposed adjacent said roller, a rider-roll contacting said rollers, and a third roller for transferring ink from the drum to the inking means of the press, of means for mounting said rollers and rider-roll for movement out of operative position, and a single means for actuating said mountings to effect said movement.

4. In an ink feeding device for printing presses, the combination with an ink-supply roll, an ink drum, a roller contacting said ink-supply roll and said drum, a second roller contacting said drum and disposed adjacent said roller, a rider-roll contacting said rollers, and a third roller for transferring ink from the drum to the inking means of the press, of means for mounting said first roller for movement away from said ink-supply roll and said drum, means for mounting said second and third rollers for movement away from said drum, means for mounting said rider-roll for movement away from said first and second rollers, an actuating member, and connection means between said member and said mounting means whereby actuation of said member effects first a movement of said rider-roll away from said first and second rollers, and then movement of said first and second rollers away from said drum, and also effects movement of said third roller away from said drum.

35 5. In an ink feeding device for printing presses, the combination with an ink-supply roll, an ink drum, a roller contacting said ink-supply roll and said drum, a second roller contacting said drum and disposed adjacent said roller, a rider-roll contacting said rollers, and a third roller for transferring ink from the drum to the inking means of the press, of means for mounting said first roller for movement away from said ink-supply roll and said drum, means for mounting said second and third rollers for movement away from said drum, means for mounting said rider-roll for movement away from said first and second rollers, an actuating member, and connection means between said member and said mounting means whereby actuation of said member effects first a movement of said rider-roll away from said first and second rollers, and then movement of said first roller away from said ink-supply roll and said drum, and then movement of said sec-

ond roller away from said drum, and also effects movement of said third roller away from said drum.

6. Ink feeding mechanism for a printing press comprising a fountain roll, an ink supply roll, a ductor roller, means mounting the ductor roller for movement into engagement with said fountain roll and ink supply roller successively, an ink drum, a transfer roller engaging said drum and also engaging said ink supply roll, a rider roll engaging said transfer roller, a second transfer roller engaging said drum, an intermediate roll engaging said second transfer roller and the inking means of the press, means mounting said rider roll for movement away from said first transfer roller, means mounting said first transfer roller for movement away from said drum, and said ink supply roll, means mounting said second transfer roller for movement away from said drum and said intermediate roll, and common actuating means for all said mounting means.

7. In an ink feeding device for printing presses, the combination with a rotary ink drum, a roller contacting said drum for transferring ink thereto, and a second roller contacting said drum for transferring ink from said drum to the inking means of the press, a rider roller contacting said first-mentioned roller, of means for mounting said first roller for movement away from and toward said drum, means for mounting said second roller for movement away from and toward said drum, means mounting said rider roller for movement from said first roller and a single means for actuating the mounting means of all said rollers to move said rollers away from and toward said drum, said means being effective solely to hold said movable rollers in normal operating position.

8. Ink feeding mechanism for a printing press comprising a plurality of contacting cylindrical members arranged to deliver ink to a printing form, and means for supplying ink to said members including a fountain, a fountain roll and a ductor roller, means operated in synchronism with the press for moving the ductor roller from a position in contact with the fountain roll to a position in contact with one of said cylindrical members, and manually operable means including a linkage connection with said moving means for moving the ductor roller whereby it may be separated from the fountain roll after the press has been stopped.

JOSEPH SINKOVITZ.
